G. DE VINCENTI

HAIR CUTTER

Filed May 17, 1921

Inventor
Gaetano De Vincenti

By

Elmer B. Bedford

Attorney

UNITED STATES PATENT OFFICE.

GAETANO DE VINCENTI, OF EDGEMOOR, DELAWARE.

HAIR CUTTER.

Application filed May 17, 1921. Serial No. 470,319.

To all whom it may concern:

Be it known that I, GAETANO DE VINCENTI, a citizen of the United States, residing at Edgemoor, in the county of New Castle and State of Delaware, have invented 5 certain new and useful Improvements in Hair Cutters, of which the following is a specification.

My said invention relates to an improved 10 hair-cutter of the type adapted to be used by a person in cutting his own hair and it is an object of the invention to provide a device of this sort which shall fit nicely in the hand of the user so that it may be operated without undue fatigue.

A further object of the invention is to provide a device of the character described 20 which shall be operated by a spring motor, as it is tiresome and inconvenient to operate clippers or like devices in cutting one's own hair.

Another object of the invention is to provide adjusting means by which the length of the hair-cut may be predetermined and 25 by adjustment of which means the hair may be cut to different length on different parts of the head.

Referring to the accompanying drawings which are made a part hereof and on which 30 similar reference characters indicate similar parts,

Figure 1 is a vertical section of my device,

Figure 2 a plan of the same with parts in 35 section,

Figure 3 a detail of one of the cutting members, and

Figure 4 shows a casing of slightly different form.

40 In the drawings reference character 10 indicates a casing having a reduced rear portion which is narrower than the body and is somewhat flattened. The lower portion of the casing at its forward end is formed with teeth 11 to co-act with the teeth of a member 12 forming in effect clippers of well-known type. The teeth at 11 may be integral with the casing or formed on a separate member attached thereto in any convenient manner.

45 The upper portion of the casing is preferably formed as a separate member 13 resting on the member 10 at 14 and engaging a groove 15 in cutter 12. Within the casing is a plate 16 attached to the upper member of the casing as by a screw 17. A second plate 55 17' spaced from the first co-acts therewith to

support a series of shafts 18, 19, 20 and 21. Shaft 18 is the shaft of a spring motor contained in a casing 22 having at its lower end a ratchet 23 coacting with the other pawl and 60 at its upper end a gear 24 engaging a pinion 25. Pinion 25 is carried by shaft 19 which also carries a gear 26 engaging a pinion 27 on shaft 20. This shaft carries at its upper end a scape wheel 28 engaging pallets 65 29, 29' on shaft 21. Shaft 21 carries a rock arm 30 engaging a block 31 slidably mounted in a slot of cutter 12.

The means for adjusting the length of the hair-cut comprises a member 32 pivoted at 70 33 and having three series of teeth 34. At its sides the member 32 has upwardly projecting slotted arms 35 and bolts 36 fixed to the sides of the casing to engage in the slots and hold the member 32 in adjusted position. 75

In the operating of the device the motor is wound up by a key 37 and is held so by a pawl engaging the ratchet 23 the cutter being held by the operator in either hand. 80 The pawl is operated by any convenient means and the motor through the connected gearing causes shaft 21 to vibrate. It will be noted that the pallets 29 and 29' are differently formed so that rotation of scape 85 wheel 28 in one direction will serve to vibrate the shaft 21 to-and-fro by the cam action of the teeth against the projections of the escapement. Vibration of the escapement will slide the segmental cutter 12 back 90 and forth over the lower cutter teeth 11. The cutter may be used without the guard 32 in the usual manner to give a close hair-cut. If the member 32 is used the lower set 95 of teeth will give a somewhat longer hair-cut as indicated in Figure 1. By loosening the nuts of bolts 36 the member 32 may be adjusted to position the second or third sets of teeth in front of the teeth 11 whereupon the length of the hair-cut will vary correspondingly. The teeth 34 act in the same manner as a comb when used by the barber, as will be obvious.

It will be evident to those skilled in the art that modifications of my device may be made without departing from the spirit of the invention and therefore I do not limit myself to the precise embodiment shown in the drawings and described in the specification but only as indicated in the appended 105 claims. I may for example, form the casing 110 with its lower surface substantially straight,

as in Figure 4, so that the tail portion 38 shall slope downwardly instead of upward as in Figure 1 and various other changes may be made in the device.

5. Having thus fully described my said invention, what I claim as new and desire to secure by Letters Patent, is:

1. In a hair cutting implement, a combined casing and handle having a reduced 10 rear portion the under side thereof sloping gradually upwardly and rearwardly, said casing carrying cutters projecting from the forward portion thereof, a motor housed within the casing, and a movable cutter 15 driven thereby and cooperating with the said cutters on the casing, substantially as set forth.
2. In a hair cutting implement, a combined casing and handle having a reduced 20 rear portion the under side thereof sloping gradually upwardly and rearwardly, said casing carrying cutters projecting from the forward portion thereof said casing having shoulders at the upper and lower forward 25 end thereof, a pair of plates fitted to the shoulders and extending longitudinally of the casing, a motor supported between said plates and a movable cutter driven thereby and cooperating with the said cutters carried by the casing, substantially as set forth.
3. In a hair cutting implement a combined hollow casing and handle having a reduced rear portion the under side thereof sloping gradually upwardly and rearwardly, a motor within the casing, a cutter operated by the motor, a comb curved transversely across the forward end of the casing and formed with a plurality of series of

teeth projecting outwardly therefrom, substantially as set forth.

4. In a hair cutting implement, a comb carried by the implement extending transversely across the front thereof, said comb having a plurality of series of teeth arranged in horizontally spaced relation, each series 45 projecting outwardly from the comb, substantially as set forth.

5. In a hair cutting implement, a combined casing and handle having a reduced 50 rear portion on the under side thereof sloping gradually upwardly and rearwardly, said casing carrying cutters projecting from the forward portion thereof, a motor housed within the casing, a movable cutter driven thereby and cooperating with the said cutters on the casing, and a comb carried by the implement and curved transversely across the front thereof, said comb having a plurality of series of teeth arranged in horizontally spaced relation, each series 55 projecting outwardly from the comb, substantially as set forth.

6. In a device for cutting hair, a comb having a plurality of series of teeth curved across the longitudinal length thereof and 60 means for mounting said comb on said device.

In witness whereof, I have hereunto set my hand and seal at Edgemore, Delaware, this sixteenth day of May, A. D. nineteen 70 hundred and twenty-one.

GAETANO DE VINCENTI. [L. S.]
